LENS CLIP

Filed Oct. 27, 1924

INVENTOR
Charles W. Dake
BY
Parker + Carter
ATTORNEY

UNITED STATES PATENT OFFICE.

CHARLES W. DAKE, OF CHICAGO, ILLINOIS.

LENS CLIP.

Application filed October 27, 1924. Serial No. 745,950.

My invention relates to improvements in lens clips, that is,—clips for fastening devices for holding the lens or front window of a headlight or floodlight or other similar light casing in place. One object of my invention is to provide a new and improved type of lens holder which may be easily applied and which will remain tight under all conditions. Another object is to provide a clip which will yieldingly hold the lens or panel in place under varying conditions of temperature, expansion and the like. Other objects of my invention will appear from time to time in the course of the specification and claims.

My invention is illustrated more or less diagrammatically in the accompanying drawings, wherein—

Figure 1 is a vertical section through a door and lens;

Figure 2 is a plan view of one of the clips;

Figure 3 is a section along the line 3—3 of Figure 2 showing in dotted lines the clip in the compressed or working position.

Like parts are indicated by like characters throughout the specification and drawings.

A is an annular ring or door adapted to be held in a headlight or other light casing by means not here shown. On the inner side of this ring or door is a groove A¹ which may extend all the way around or may be discontinuous as the case may be. On the forward side is a flange A² which overhangs clear around the inner periphery of the door. A³ is a lens or glass panel flanged at A⁴ to engage a packing ring A⁵ which is slidably mounted in the ring A and abuts against the overhanging side of the flange A².

B is the lens clip. It has a downwardly bent tail B¹ adapted to engage the groove or abutment A¹. It is slotted at B² to slidably engage a screw B³ threaded in the ring A and is downwardly and then upwardly recurved at B⁴ so as to provide curved surfaces adapted one of them to engage the inner periphery of the ring A and the other to engage the rear periphery of the packing ring A⁵.

When this clip is dropped into place the screw can be passed through the slot and then tightened up. This compresses the clip and causes it to press against the abutment A¹ at one end and against the inner wall of the ring at the other. Further movement

lengthens the clip causing it also to press against the lens and force it forward against the overhanging flange A². This pressure somewhat upsets the clip and causes it to exert a spring pressure against the lens. If the screw is screwed up far enough, the lens will be firmly though yieldingly seated in such manner that vibration or expansion of the parts can be compensated for by the spring action of the clip and the lens will be at all times held in proper operating position.

It will be evident that while I have shown in my drawings an operative device, still many changes might be made in the size, shape and disposition of parts without departing materially from the spirit of my invention and I wish, therefor, that my showing might be taken as in a large sense diagrammatic.

I claim:

1. A closure for lamp housings and the like comprising an annular inwardly flanged ring, a panel contained within the ring and adapted to rest against the flange, an abutment on the opposed side of the ring and a plurality of holding elements adapted to be separately wedged between the abutment and the panel, and means associated with the holding elements for anchoring them in position and for adjusting the pressure exerted by them.

2. A closure for lamp housings and the like comprising an annular inwardly flanged ring, a panel contained within the ring and adapted to rest against the flange, an abutment on the opposed side of the ring and a plurality of flexible holding elements adapted to be separately wedged between the abutment and the panel and means associated with the holding elements for anchoring them in position and for adjusting the pressure exerted by them.

3. A closure for lamp housings and the like comprising an annular inwardly flanged ring, a panel contained within the ring and adapted to rest against the flange, an abutment on the opposed side of the ring and a plurality of flexible holding elements adapted to be separately wedged between the abutment and the panel, said holding elements comprising clips adapted to engage the ring at one point removed from the panel and at another point adjacent the panel, and a screw threaded in the ring and adapted to

compress the clip to slide that part which engages the ring near the panel against and hold it in contact with the panel.

4. A closure for lamp housings and the like comprising an annular inwardly flanged ring, a shallow groove on the inner periphery thereof removed from the flange having an aubutment surface opposed to the flange, a plurality of spring clips each having a tail adapted to engage such surface and a bearing element adapted to engage the inner wall of the ring, a screw associated with each clip

threaded in the ring, the clip being slotted where the screw passes through it, a panel contained within the ring adapted to engage the flange, the clip having a bearing surface adapted to engage the panel and when the screw is tightened force the panel against the flange. 15

Signed at Chicago, county of Cook and 20
State of Illinois, this 23rd day of October,
1924.

CHARLES W. DAKE.
